PROCESS FOR THE MANUFACTURE OF NON-
DEPOSITING LIQUID SOAPS

Louis Friedrich, Wilhelm Pape and Hans Umbach,
Dusseldorf-Benrath, Germany, assignors to
the firm Henkel & Cie. Gesellschaft mit be-
schränkter Haftung, Dusseldorf, Germany

No Drawing. Application February 23, 1934, Se-
rial No. 712,656. In Germany March 3, 1933

5 Claims.

(CL 87—5)

Transparent liquid soaps exhibit more or less the property of separating turbid matter which slowly settles to the bottom. Troublesome and expensive measures are therefore necessary in order to manufacture good liquid soaps. Such measures consist for example in the use of special fat mixtures, in cooling, filtering and long storage and the like. Even well-cooled liquid soaps after filtration often exhibit, however, the same unpleasant property to a greater or lesser degree.

Furthermore, it is known that transparent liquid soaps do not, in general, have any favorable action upon the human skin, which in fact with the use of clear liquid soap, even liquid soap which is completely neutral, often becomes rough and cracked.

The present invention relates to a liquid soap with which the aforesaid disadvantages do not occur.

20 This new non-depositing liquid soap is characterized by containing finely dispersed turbidity agents, preferably superfatting agents. It has the usual concentration of liquid soaps and contains the turbidity agents in a fine emulsion-like dispersion, so that the said agents are not deposited.

The addition of non-depositing turbidity agents according to the invention has the effect of likewise preventing the deposition of the turbidity-producing substances which are present per se in liquid soaps. If a liquid soap is made from the usual fat mixture for liquid soaps, it exhibits turbid matter which settles to the bottom, for example in the course of three weeks. If, on the contrary, the same liquid soap is mixed according to the present invention, either immediately after or during manufacture, with finely dispersed turbidity agents, the soap thus manufactured does not exhibit any bottom sediment, even after being stored for three weeks, but on the contrary the turbidity-producing substances derived from the fat mixture are held in suspension with and by the additional substances.

45 The manufacture of the new liquid soaps may be carried out in different ways. For instance, the desired turbidity agents, preferably superfatting agents, may be added to liquid soaps. The turbidity agents may, however, be allowed to form in the liquid soap, or may be added to the starting materials employed for the manufacture of the liquid soaps. If desired, wetting and emulsifying agents may be added to prevent the turbidity agents from settling.

55 In many respects, the new liquid soaps possess

advantages over the liquid soaps known heretofore.

No special fat mixtures are employed in their manufacture. Likewise, the troublesome cooling and filtration is obviated, since any turbid matter which separates out is concealed by the content of turbidity agents. A long storage time is likewise not necessary but on the contrary the soaps are ready for export and sale immediately after their manufacture.

If the turbidity agents consist of superfatting agents, then the new liquid soaps, in regard to their action upon the skin, are in no way inferior to first grade toilet soaps.

As turbidity agents for the liquid soaps superfatting agents are preferably employed, such as for example wool fat, higher fatty alcohols, i. e. alcohols having eight and more carbon atoms, the higher alkyl ethers of polyhydric alcohols, for example of the glycol, the glycerol, the polyglycol or the polyglycerol, the term higher alkyl ethers denoting those having eight and more carbon atoms, also paraffin wax and the like. Other insoluble organic or inorganic substances may be employed as turbidity agents, as for example wood powder, clay, calcium carbonate and the like. These inorganic turbidity agents are also capable of maintaining in suspension the turbidity agents derived from the mixture.

The term "turbidity agent", as employed in the specification and claims, is intended to embrace those substances having the following physical properties: (1) The property of principally reflecting and not absorbing light, (2) the particles making up the substances must be of such dimension that the light is reflected therefrom diffusely. Too small particles (below the limit of the colloids) and particles that are too large (particles of macroscopic size) cannot be used.

As wetting and emulsifying agents, the known agents may be employed.

Examples

(1) 4500 kilograms of a fat mixture suitable for the manufacture of liquid soap is melted with 1050 kilograms of resin and 600 kilograms of paraffin wax (melting point 50 to 52° C.), 600 kilograms of wool fat and 150 kilograms of bleached Montan wax. The melt is saponified with 2400 kilograms of a 50-per cent caustic potash solution in the presence of 1500 kilograms of water, and the finished soap is diluted with 1700 kilograms of water. The reaction mass is then mixed with molten stearin until the free alkali

present is neutralized and there is a low acid number. A liquid soap is obtained.

(2) To 2500 kilograms of a suitable fat mixture consisting of cocoanut oil, castor oil and olive oil are added 600 kilograms of paraffin wax having a melting point of 50° C. The melt is then saponified with 1200 kilograms of a 50 per cent. caustic potash solution diluted with 700 kilograms of water. 700 kilograms of stearic acid are stirred molten into the resulting unsalted-out soap mass, and thereupon the mass is diluted with 8000 kilograms of hot water.

(3) To 2500 kilograms of cocoanut oil are added 75 kilograms of Montan wax. The melt is saponified with 1200 kilograms of a 50 per cent. caustic potash solution diluted with 700 kilograms of water. The resulting un-salted-out soap mass is then mixed with 750 kilograms of molten stearic acid and is then diluted with 8500 kilograms of water.

The stearin may be replaced entirely or partly by a wax acid of the Montan series.

(4) 500 kilograms of a 25 per cent. liquid soap, the fat mixture of which consists of 24 parts of tallow, 12 parts of cocoanut oil and 8 parts of castor oil are mixed with a 10 per cent. solution of calcium chloride until no more lime soap is precipitated. The lime soap is filtered off and washed. The washed lime soap is introduced into a boiling solution of 20 kilograms of potash in 500 kilograms of water and is boiled for about one to two hours. The still unconverted quantity of potash, amounting to about 1 to 2 per cent. of the reaction mass, is then reacted with sufficient 35 palm kernel oil fatty acid to give an acid number of 3 to 5, calculated on the soap milk. The quantity of lime soap employed may also be manufactured by the direct method. The calcium carbonate formed in the double decomposition 40 does not settle and also maintains any other turbidity forming matter in suspension.

(5) 94 kilograms of cocoanut oil and 3 kilograms of Montan wax are saponified luke-warm with 56 kilograms of a 47 per cent. caustic potash 45 solution (Soap A).

Furthermore, 385 kilograms of a 1 per cent. solution of water-soluble cellulose (methyl cellulose), which serves for emulsifying the superfatting agent and the other turbidity producing substances, are mixed with 6.8 kilograms of a solution of potassium hydroxide. With this mixture 11.1 kilograms of resin and 5.6 kilograms of castor oil are saponified (Soap B).

After saponification, these two liquid soaps A 55 and B are combined. Into the liquid soap thereby obtained 25 kilograms of Montan wax acid are introduced in the molten state with energetic stirring. A non-depositing liquid soap milk of good properties is obtained.

We claim:—

1. In the manufacture of potash liquid soaps which normally involve a filtering or other purifying process, the step of incorporating with said soaps, which contain an inherently present material which imparts a turbidity to said soaps and tends to settle out of said soaps, a substantial quantity of a superfatting substance comprising a member selected from the group consisting of stearic acid, Montan wax, paraffin wax, wool fat, 10 higher fatty alcohols, and higher alkyl ethers of glycol, glycerol, polyglycol and polyglycerol, said superfatting substance being present in sufficient quantity to impart a definite turbidity to said soap, and preponderating over the turbidity 15 power of any normally sediment-forming material inherently present in said soap.

2. In the manufacture of potash liquid soaps which normally involve a filtering or other purifying process, and which contain an inherently 20 present material which imparts a turbidity thereto and normally tends to settle out, the process of melting a fat mixture suitable for the manufacture of said liquid soap, paraffin wax, wool fat and Montan wax, saponifying the mixture with a 25 caustic potash solution and diluting the resultant soap with water, said paraffin wax, wool fat and Montan wax being present in sufficient quantity to impart a definite turbidity to said soap and preponderating over the turbidity power of any 30 normally sediment-forming material inherently present in said soap.

3. The process set forth in claim 2, together with the further step of mixing the diluted soap with molten stearin until the free alkali present 35 is neutralized.

4. In the manufacture of potash liquid soaps which normally involve a filtering or other purifying process, and which contain an inherently present material which imparts a turbidity 40 thereto and normally tends to settle out, the process of melting cocoanut oil, castor oil and olive oil with paraffin, saponifying said melt with a caustic potash solution, diluting the resultant soap with water, and incorporating with said 45 soap during one of the aforesaid steps of manufacture, a quantity of stearic acid, said paraffin and stearic acid being present in sufficient quantity to impart a definite turbidity to said soap and preponderating over the turbidity power of any 50 normally sediment-forming material inherently present in said soap.

5. The process set forth in claim 4, wherein said stearic acid is incorporated with said soap subsequent to saponification thereof. 55
